W. H. MARSHALL. PATENTED AUG. 18, 1908.
CEMENT BURIAL VAULT.
APPLICATION FILED MAR. 16, 1908.

2 SHEETS—SHEET 2.

UNITED STATES PATENT OFFICE.

WILLIAM HARVEY MARSHALL, OF NEW PARIS, OHIO, ASSIGNOR OF ONE-HALF TO CHARLES H. MARSHALL, OF NEW PARIS, OHIO.

CEMENT BURIAL-VAULT.

No. 896,223.

Specification of Letters Patent. Patented Aug. 18, 1908.

Application filed March 16, 1908. Serial No. 421,460.

To all whom it may concern:

Be it known that I, WILLIAM H. MARSHALL, a citizen of the United States, residing at New Paris, in the county of Preble and 5 State of Ohio, have invented certain new and useful Improvements in Cement Burial-Vaults; and I do declare the following to be a full, clear, and exact description of the invention, such as will enable others skilled in 10 the art to which it appertains to make and use the same.

This invention relates to new and useful improvements in cement burial vaults.

The principal object of the invention is the 15 production of simple and efficient operating means for automatically locking the lid or cover in position and which cannot be operated to release the lid or cover.

With this and other objects in view, the invention consists of certain novel features of 20 construction, combination and arrangement of parts, as will be more fully described and particularly pointed out in the appended claims.

25 In the accompanying drawings:—Figure 1 is a sectional perspective view of a vault constructed in accordance with the invention; Fig. 2 is a transverse sectional view; Fig. 3 is a horizontal section taken on line 3—3 of Fig. 2, and, Fig. 4 is a vertical longitudinal section taken on line 4—4 of Fig. 3.

In the embodiment illustrated, a vault constructed in accordance with the invention essentially comprises side and end pieces 1 35 and 2 respectively, a bottom 3 and a lid or cover 4.

In carrying out the invention, the side pieces are grooved at opposite side edges and in their inner faces near opposite ends 40 throughout the length and width of the same, as at 5, the grooves in the upper side edges of the side pieces being preferably of somewhat greater depth than those of the lower or bottom side edges and ends, the purpose of which will be disclosed.

45 In practice the bottom 3 is formed at opposite side edges and ends with tongues 6 designed to fit in the grooves in the bottom edges of the side and end pieces, the end pieces 2 being also formed at opposite ends with vertically extending tongues 7 designed to fit in the grooves in the inner faces and near the ends of the side pieces.

By employing the construction above de-

scribed it will be evident that the parts when 55 once assembled are securely held in position.

The side pieces 1 of the vault are also provided with longitudinally spaced series of upright reinforcing bars 8 the upper ends of which extend or project into the grooves in 60 the upper edges of the same. The side pieces which are made of concrete or other suitable material may be further strengthened by a series of vertically spaced longitudinally extending reinforcing rods 9 which may or may 65 not be connected with said bars 8 as may be desired.

The cover of the vault which is also made of concrete or analogous material and is preferably in one continuous piece is also strengthened 70 by a series of longitudinally spaced transversely extending metallic reinforcing bars 10 near opposite ends of which are preferably attached eye bolts 11, the eyes of which project slightly above the cover and 75 are adapted to be engaged by suitable means during the operation of lowering the cover into the grave. These eye bolts also add further strength to the cover.

80 A particular feature of the invention resides in the provision of means for automatically locking the cover in position. As shown, this means comprises upright spring arms 12, a pair of which are attached at their lower ends to opposite faces of the upper projecting end of each of the bars 8, the extreme upper ends of said arms terminating in downwardly inclined engaging hooks 13 designed to engage oppositely extending upwardly inclined catches 14, formed in the heads near 90 the lower ends of depending arms 15, attached to the reinforcing bars 10 in position to project into the grooves in the upper edges of the side pieces of the vault to position the cover thereon.

95 The lower ends of the heads of the depending arms 15 are produced beyond the engaging portions 14 and terminate in sharp V-shaped portions 16 which easily spread or force apart the upper ends of the spring arm 13 during the operation of placing the cover in position.

100 From the foregoing description taken in connection with the accompanying drawings, the construction and operation of the invention will be readily understood without requiring a more extended explanation.

105 Various changes in the form, proportion

and the minor details of construction may be resorted to without departing from the principle or sacrificing any of the advantages of the invention, as defined in the appended 5 claims.

Having thus described my invention, what I claim as new and desire to secure by United States Letters-Patent is:—

1. A sectional vault comprising side pieces 10 formed in their upper side edges with grooves, reinforcing bars extending transversely through the side pieces, the upper ends of said bars projecting into said grooves, a pair 15 of spring arms provided with hook portions attached to opposite faces of the projecting end of each of the reinforcing bars, and a cover provided with depending arms adapted to enter the grooves of the side pieces, the lower ends of said arms provided with catch 20 portions adapted to be engaged by the hook portions of the spring arms.

2. A sectional vault comprising side pieces 25 formed in their upper edges with grooves, reinforcing bars extending transversely through the side pieces, the upper ends of said bars projecting into said grooves, a pair 30 of spring arms provided at their upper ends with hook portions, attached to opposite faces of the projecting end of each of said reinforcing bars, a cover, reinforcing bars ex-

tending transversely through the cover, and arms depending from said last mentioned reinforcing bars in position to enter the grooves of the side pieces, said arms having catch portions adapted to be engaged by the hook 35 portions of the spring arms.

3. A sectional vault comprising side pieces formed in their upper edges with grooves, reinforcing bars extending transversely through the side pieces, the upper ends of 40 said bars projecting into said grooves, a pair of spring arms provided at their upper ends with hook portions, attached to opposite faces of the projecting end of each of said reinforcing bars, a cover, reinforcing bars extending transversely through the cover, and 45 arms depending from said last mentioned reinforcing bars in position to enter the grooves of the side pieces, said arms having catch portions adapted to be engaged by the hook 50 portions of the spring arms, and with V-shaped portions below their catch portions.

In testimony whereof I have hereunto set my hand in presence of two subscribing witnesses.

WILLIAM HARVEY MARSHALL.
